UNITED STATES PATENT OFFICE.

EMILE BOURDELLES, OF PARIS, FRANCE, ASSIGNOR TO SCHNEIDER & CIE., OF PARIS, FRANCE, A LIMITED JOINT-STOCK COMPANY OF FRANCE.

BREECH-LOADING GUN.

1,092,763.

Specification of Letters Patent.

Patented Apr. 7, 1914.

Application filed April 17, 1913. Serial No. 761,844.

To all whom it may concern:

Be it known that I, EMILE BOURDELLES, a resident of Paris, France, and a citizen of France, have invented a new and useful Improvement in Breech-Loading Guns, which is fully set forth in the following specification.

This invention relates to breech loading guns.

10 The recoil apparatus hitherto known, necessitates the employment of a large recoiling mass of the gun, so that the great strength of modern steel cannot be turned to account in order to lighten the guns. In 15 other words the gun proper might be made of less thickness while providing the necessary resistance to the pressures developed in firing, if it were not necessary to increase its mass with a view to limiting the recoil 20 by the known means that are available.

According to the present invention, the excess mass necessary for the employment of the known recoil means, instead of being distributed over the barrel of the gun, is 25 employed in the form of an auxiliary gun of different caliber, this second gun remaining constantly connected with the first in order to increase the recoiling mass of the latter and being adapted to be used in two positions that is to say fixed to the exterior or fitted in the principal gun. The result of 30 this arrangement is that without altering the total recoiling mass in any way, it is possible, with the same material, to fire projectiles of two different calibers according as 35 the auxiliary gun is arranged in one or other of the two positions mentioned above. On the one hand it is thus possible to profit by the strength of modern steels so as to lighten 40 each of the guns and on the other hand two guns are united upon one and the same carriage and either of these guns can be used according to requirements and fighting conditions, this representing an important economy 45 in cost of construction and in personnel. It will of course be understood that the details of the means rendering it possible to connect and unite the principal gun with the auxiliary gun (which are always connected for the recoil) may vary at will.

In order that the said invention may be clearly understood and readily carried into

effect, the same will be described more fully with reference to the accompanying drawings in which:—

55

Figure 1 is a longitudinal sectional elevation showing the united guns in the position that they occupy when using the gun of larger caliber. Figs. 2 and 3 are corresponding cross sections on the lines A—A 60 and B—B respectively of Fig. 1. Fig. 4 is a sectional elevation showing the united guns in the position that they occupy when using the gun of smaller caliber. Fig. 5 shows in front elevation and inside elevation, 65 respectively, a protecting ring for the threads in the muzzle of the gun.

In the example illustrated, the principal gun *a* of medium caliber is made of high resistance steel so that its thickness and mass 70 can be reduced. The excess mass necessary for the operation of the recoil brake is utilized, in accordance with the present invention for the construction of the auxiliary gun, *b* of smaller caliber, also made of high 75 resistance steel. The two guns are assembled in such a manner as to recoil together and they are provided with means which permit of effecting this assemblage rapidly for firing at will projectiles of either caliber. 80

In the example illustrated, the gun *a* of larger caliber comprises external retaining or fixing members for the gun, *b*. Thus at the front of the gun *a*, in proximity to its muzzle a collar *d* with internal interrupted 85 threads *d'* may be arranged, *d*² representing the grooves between the threads. The auxiliary gun is provided with corresponding interrupted threads *b*² separated by grooves *b'*. At the rear, a similar fixing device may be 90 employed; it is, however, sufficient to provide a retaining nose *c* upon a projection from the breech of the gun *a* and beneath which the barrel *b* engages (Figs. 1 and 2).

It will readily be understood that the barrels *a* and *b* thus assembled as shown in Figs. 1 to 3, recoil together when firing projectiles of a caliber corresponding to the barrel *a*; the barrel *b* with the fixing members, completes the mass necessary for the 100 operation of the recoil brake. If it be desired to utilize the barrel *b* it is only necessary to angularly displace this barrel and then to draw it forward. The barrel *a* is pro-

vided in an extension *g* having threads *a'* interrupted by grooves *a²*. The barrel *b* is of course of such a length that after screwing into the barrel *a* its rear face comes at 5 the proper distance from the breech block *e*. It will be understood that the breech may be of any known type and similarly all the other usual parts such as firing devices, brakes and so forth may be of any suitable 10 construction. The barrel *b* may, if desired, be centered at the rear extremity or at some suitable point of the chamber of the gun *a*, by means of a detachable ring *f*. The tubes *a* and *b* being assembled in the 15 position indicated in Fig. 4 it will readily be understood that they recoil together when firing projectiles of small caliber. The system of united guns can be regarded as constituting a small caliber gun equal in weight 20 to guns as hitherto constructed and furnishing the additional facility of firing projectiles of larger caliber; or inversely a medium caliber gun is obtained, the weight of 25 which is equal to that of the usual guns of the same caliber, but affording the possibility 30 of firing projectiles of small caliber. The threads *a'* for fixing the barrel *b* in the gun *a* may be protected from the erosion of the gases during the firing of projectiles of 35 the larger caliber, that is to say when the guns are arranged as shown in Fig. 1; this protection may be afforded by a sleeve *h* represented separately in front elevation and in side elevation in Fig. 5 and provided 40 externally with interrupted threads or collars. This sleeve is of the same length as the extension *g*.

Although for practical purposes it is unnecessary to consider the connection of more 45 than two guns of different caliber, it is obvious that the invention described above is also applicable to a combination of more than two guns, and that in order to unite guns of three different calibers, for example, it would only be necessary to provide additionally upon the barrel *a*, fixing members for a gun of smaller caliber than that of the gun *b*.

What I claim and desire to secure by Letters Patent of the United States is:—

50

1. In breech loading ordnance adapted for use with recoil mechanism, the combination of a primary gun and a secondary gun permanently associated therewith, the metal of which furnishes the additional mass necessary for operating the recoil mechanism when the principal gun is fired, said secondary gun being adapted to fit the bore of the primary gun for firing smaller projectiles.

55

2. In ordnance adapted for use with recoil mechanism, the combination of a primary gun and a secondary gun of different diameter permanently associated therewith, the metal of which furnishes the additional mass necessary for operating the recoil mechanism when the principal gun is fired.

60

3. In a breech loading gun adapted for use with recoil mechanism, the combination of a primary gun having a threaded muzzle and a secondary gun of different diameter permanently associated therewith, the metal of which furnishes the additional mass necessary for operating the recoil mechanism when the principal gun is fired, and means for securing said guns together comprising on the principal gun a threaded collar and a retaining nose and on the secondary gun a threaded section adapted to engage either the threads of said collar or said threaded muzzle.

65

4. In combination, a gun having a muzzle provided with internal screw threads, a second gun adapted to fit the bore of the first-named gun and having external threads to engage those of said muzzle, said guns being permanently associated for the purpose described, and a ring for shielding the muzzle threads on the first-named gun when the latter is used for firing.

70

In testimony whereof I have signed this specification in the presence of two subscribing witnesses.

EMILE BOURDELLES.
